WARNING AND STOPPING DEVICE FOR
KNITTING MACHINES

Carl Mitschele, Pforzheim, Germany

Application December 27, 1938, Serial No. 247,955
In Germany August 27, 1936

5 Claims. (CL 66—158)

The invention relates to a warning or stopping device for knitting machines which is influenced by irregularities in the running of the thread or yarn, such as the passage of a knot or slub, 5 breakage of the yarn or the like, the yarn passing between two guides which are arranged close behind one another and at least one of which is pivotally mounted and acts upon the warning or stopping device. In hand operated machines, 10 warning is generally effected by means of signals and in motor driven machines it is effected mechanically or electrically by automatic stopping of the machine.

The purpose of such devices is above all to 15 give immediate warning of small or large knots of any size, and even thickened portions of yarn in order to prevent defects in the fabric and trouble in the machine. At the high running speed the yarn does not support any load owing 20 to the danger of breakage.

In order to ensure immediate and satisfactory warning of knots and the like, it is necessary to enclose the yarn on all sides at a guiding place so closely that warning may be given even of 25 thickened portions of yarn. On the other hand, the passage of the knot should not produce excessive yarn tension, so that the knot will be signalled but can escape without hindrance.

In the devices known heretofore, the narrowing 30 of the yarn passage orifice for adaptation to the thickness of the yarn or to the size of the knots was effected at the expense of excessive yarn tension, the danger of breakage being, however, considerably increased. Other devices possess 35 pivotal guides but with a calibrated passage for the yarn. Such devices, however, are unreliable in operation because large knots result in breakage of the yarn, while small knots pass through without any warning being effected. It is clear 40 that such devices which, in addition to pivoting, also have to exert some contact pressure, increase still further the loading of the yarn.

For obviating the above-mentioned disadvantages, the device according to the invention is 45 so constructed that in known manner the first guide is stationary and the second is pivotal and the outwardly pivotal guide, which is at the boundary of unstable equilibrium and is open at one side, and the stationary guide are adjustable 50 relatively to one another in accordance with the thickness of the yarn, and in the position of readiness form a common passage orifice which encloses the yarn on all sides and which, upon a knot or the like impinging on the pivotal bearing 55 is very rapidly increased in size due to a

slight outward pivoting of said bearing, and consequently ceases to enclose the yarn and allows the knot to escape without hindrance at the open side of the pivotal guide.

In this construction of the invention, during 5 the passage of a yarn knot or thickened portion, the latter owing to the guides being positioned one below the other, first impinges on the stationary guide, the yarn being bent and thereby 10 pressed under the movable guide. In an improved construction of the invention, the arrangement is such that the yarn knot or thickened portion is engaged simultaneously by both guides so that it can escape without bending and 15 without one-sided stressing of the yarn tension. This also dispenses with enclosure of the yarn on all sides.

This construction is characterized in that two 20 outwardly pivotal guides in unstable equilibrium are situated adjacent one another in the position of readiness and with their adjacent open ends enclose the yarn on all sides or partly, in accordance with its thickness, and upon the occurrence of a knot or thickened portion of yarn, 25 simultaneously pivot outwardly in known manner, independently of the form of the knot. In this case, both an audible and visual signal is operated thereby dispensing with the tedious search for the source of the fault.

Two constructions of a device according to 30 the invention are shown diagrammatically by way of example in the accompanying drawings wherein:

Figures 1 to 4 show one construction, Figure 1 being the basic position of the device and Figure 35 2 the altered position of the device after the arrival of a knot. Figure 3 the position in the case of exhaustion of the yarn or yarn breakages, seen from the side and Figure 4 the yarn passage seen from above on a larger scale.

Figures 5 to 7 show the second construction, Figure 5 showing the device in the position of readiness, Figure 6 a part of the device in perspective and Figure 7 the device after the arrival 40 of a knot.

The yarn *a*, which for example has a knot *a*₁ and a thickened portion *a*₂ is first guided by a guide opening *b*₁ provided on the stationary frame *b*. In this guide opening, the yarn *a*, *a*₁, *a*₂ can only yield inwardly, that is to say towards the right in Figure 1, but not on the contrary outwardly, that is to say to the left in Figure 1. From this guide, the yarn is introduced into a groove *d*₁ recessed in the end of a tilting lever *d* mounted at *d*₂ on the support *c*. Unlike the op- 50 55

eration of the guide b_1 , in this case the yarn cannot yield inwardly but only outwardly. In the basic position of the tilting lever d (see Figure 1), therefore, the yarn a is entirely enclosed by the two guides but in such a manner that the 5 yarn has a slight play in the guide b_1 and groove d_1 so that no friction is set up against the yarn. If now the knot a_1 comes within the region of the guide b_1 , the place of the knot is bent in the 10 guide b_1 by half the amount of the increase between the normal yarn thickness and the thickness of the knot, the knot or the thickened portion of yarn pressing very effectively under the groove d_1 . To enable the knot or thickened portion a_2 to escape from the guide b_1 and groove d_1 again, the tilting lever d has first to make, at its 15 arm having the groove d_1 an upwardly yielding pivotal movement (see Figure 2). This is carried out so that the knot a_1 or a_2 can escape conveniently without producing any considerable 20 yarn tension, and at the same time, in consequence of the downward movement of the end of lever arm d which has the claw d_3 , the claw d_3 releases a drop lever e , the latter owing to its 25 slight excess weight swinging out on its pivot e_1 and striking a bell f , or in the case for example of power machines, automatically stopping the machine electrically. It is important that the 30 centre of gravity of the tilting lever d is arranged on the same side as the groove d_1 fairly close to its pivot d_2 so that there is almost unstable equilibrium. By means of the set screw k , the support c may be moved forward and with it the drop lever e , thus exactly adjusting the 35 passage orifice for the yarn a to any yarn thickness.

Warning or stoppage of a motor-driven machine is likewise effected by the drop lever e also in the case of yarn breakages or exhaustion 40 of the spools, as is shown in Figure 3.

After leaving the passage orifice for knots and thickened portions of yarn, the yarn a is first guided by a stationary yarn guide b_3 , mounted on a frame rail b_2 . Located above this stationary guide is a yarn feeler lever g pivoted on the pin g_1 . 45 If the yarn breaks between the machine and the yarn tensioning device not shown in the drawings, the yarn is no longer drawn taut and bends in consequence of the oblique position of the yarn feeler lever g which then swings on the arc g_2 . 50 An intermediate lever h , one lever arm of which rests on the yarn feeler lever g , also drops with the yarn feeler lever, its right-hand lever arm h_1 moving upwardly and pressing the lever arm i_1 55 of a further lever i , i_1 upwardly and the other lever arm i thereof downwardly, the latter pressing on the wire support d_4 and releasing the claw d_3 which supports the drop lever e . The end of the yarn a is also signalled in the same way (see 60 Figure 3), but with the difference that in this case the yarn is drawn entirely out of the elements b_2 , g . In this case also, however, the yarn a_3 bends even before, once only a small amount of yarn is left. In order to prevent any pressure 65 or hard contact on the guided yarn, the levers g , h and i , i_1 are made of light wire. As with the exception of the drop levers h and g , the other levers i , i_1 and d which have an influence on the 70 yarn a are in almost unstable equilibrium, the yarn a passes through the yarn testing places practically without any additional tension.

In the construction according to Figures 5, 6 and 7, the yarn a with its knots a_1 and thickened portions a_2 passes through the orifice l_1 of the stationary support in the frame l , and between

the two outwardly pivotal guides m , m_1 . In the position of readiness, the two guides enclose the yarn either completely or only partly. Their ends may therefore be of different constructions. They either possess each a semicircular or arcuate 5 opening, both openings when joined together forming a yarn passage of circular oval or other shape, or a slit-shaped opening formed by rod-like or bridge-like guide ends. In both cases, adjustment in accordance with the yarn thickness 10 may be made either on both or only on one yarn guide. The adjustment is shown particularly clearly in Figure 6, where the sheath-like guide m_1 slides over the rail-shaped end of the tilting lever d and is fixed by a wing nut n . 15

If a knot a_1 enters the passage orifice, it engages the two guides simultaneously at least at two opposite points, whereby the two guides, which are in unstable equilibrium, cease to enclose the yarn even in the event of a slight impact and tilt upwardly and outwardly in a brief but wide angle of swing, the yarn being simultaneously released without bending or danger of breakage being possible. The drop lever e is released by the downward movement of the lever 25 arm with the claw d_3 situated on the other side of the pivot d_2 . Owing to the excess weight of the drop lever e over the disc e_2 now swinging out on the other side of the pivot, the said drop lever strikes the bell f . The disc l_2 which is of particularly recognisable appearance and is fixed to the frame l by means of the bracket l_3 is simultaneously rendered visible. In the case of motor-driven machines where automatic electrically operated stoppage is provided in place of the signal 30 by bell, this identification disc is of particular significance, as generally a large number of knot signalling devices, for example twenty or more, are employed on one machine. The source of the trouble may thus be ascertained with certainty. 40

To prevent thickened portions of yarn or knots which are situated only on one side of the yarn from lifting the guide m alone, there is situated at one or both ends of the transverse member 45 of the latter, a catch or dog o which, upon the outward movement ensures the simultaneous release of the guide m_1 . The other parts of the device do not differ from the construction according to Figures 1 to 4 and have been provided with 50 the same references.

Warning of yarn breakages and spool exhaustion and stoppage of the machine in the case of motor drive is effected in the manner already 55 described in connection with the first construction.

I claim:

1. A warning or stopping device for knitting machines which is influenced by irregularities in the running of the yarn, such as the passage of 60 knots, breakage of the yarn or the like, wherein the yarn passes through two guides arranged close behind one another, at least one of which is pivotally mounted and acts upon the warning or stopping device, characterised in that the first guide is stationary and the second is pivotal, and that the outwardly pivotal guide, which is situated at the boundary of unstable equilibrium and is open at one side, and the stationary guide are 65 adjustable relatively to one another in accordance with the yarn thickness and in the position of readiness from a common passage orifice which encloses the yarn on all sides and which, upon a knot or the like impinging on the pivotal guide 70 is very rapidly increased in size, consequently 75

ceases to enclose the yarn and allows the knot to escape without hindrance at the open side of the pivotal guide.

2. A device as claimed in claim 1, characterised in that a yarn feeler lever operative in the event of yarn breakage and exhaustion of the spool upon its release acts through intermediate levers on the pivotal guide.

3. A device as claimed in claim 1, characterised in that two outwardly pivotal guides situated in unstable equilibrium are adjacent in the position of readiness and between their adjacent open sides provide a passage for the yarn appropriate to its thickness, and on the arrival of a knot or

thickened portion of yarn swing outwardly simultaneously in known manner, independently of the form of the knot.

4. A device as claimed in claim 1, characterised by the provision of an identification disc and means for exposing it simultaneously with the actuation of a bell signal.

5. A device as claimed in claim 1, characterised by the provision of an identification disc and means for exposing it simultaneously with the actuation of means for automatically stopping the machine.
